UNITED STATES PATENT OFFICE

112,379

DESIGN FOR A POWER LAWN MOWER

Lester B. Roth, Prophetstown, Ill.

Application August 15, 1938, Serial No. 79,350

Term of patent 14 years

To all whom it may concern:

Be it known that I, Lester B. Roth, a citizen of the United States, residing at Prophetstown, in the county of Whiteside and State of Illinois, have invented a new, original, and ornamental Design for a Power Lawn Mower, of which the following is a specification, reference being made to the accompanying drawings, forming a part thereof, in which—

Fig. 1 represents a side elevational view of a power lawn mower showing my new design;

Fig. 2 represents a front elevational view thereof; and

Fig. 3 represents a plan view thereof.

I claim:

The ornamental design for a power lawn mower, as shown.

LESTER B. ROTH.
